United States Patent Office.

J. C. YOUNG, OF TOLEDO, OHIO.

Letters Patent No. 96,295, dated October 26, 1869.

IMPROVED SASH-HOLDER.

The Schedule referred to in these Letters Patent and making part of the same.

To all whom it may concern:

Be it known that I, J. C. YOUNG, of Toledo, in the county of Lucas, and State of Ohio, have invented a new and useful Improvement in Window-Sash Fasteners; and I do hereby declare that the following is a full and exact description thereof, reference being had to the accompanying drawings, and to the letters of reference marked thereon.

My invention consists of the arrangement of a pinion provided with an axle, which is adjustable longitudinally upon its bearings, in combination with a spring and toothed bar.

In the accompanying drawings—

Figure 1 is a back view of a window-frame, with my improved fastening attached, a portion of the casing and of the metallic box being cut away, better to show the pinion engaging with the toothed bar on the sash.

Figure 2 is a detached lateral view of a portion of the window-frame, with my fastener attached.

In the drawings, the window-frame is shown at A, the casing at B, and the sash at C, upon which is fastened a toothed bar, E.

Fastened in one side of the frame is a metallic box, D, with bearings for the axle F, of the pinion G.

Upon the axle is a coiled spring, H, which presses the pinion toward the front of the window-frame, and thus locks the pinion in the box D, as seen in fig. 1. In this position of the pinion, the sash is also locked.

By placing a key, I, on the end of the axle F, as seen in fig. 2, the axis and pinion are easily pressed back, compressing the coiled spring, and unlocking the pinion, when the window-sash may be raised or lowered at pleasure.

Upon withdrawing the key, the coiled spring forces the pinion forward and locks the sash.

Having fully described my invention,

I claim the adjustable pinion and axle, with the tooth-bar and spring, when the latter is arranged to act upon the pinion, so as to lock the sash, in the manner substantially as described.

J. C. YOUNG.
